UNITED STATES PATENT OFFICE.

ARTHUR F. CASE, OF CLEVELAND, OHIO, ASSIGNOR TO THE WELLMAN-SEAVIER MORGAN COMPANY, OF CLEVELAND, OHIO, A CORPORATION OF OHIO.

FUELING BARGE.

1,427,091.

Specification of Letters Patent. Patented Aug. 29, 1922.

Application filed May 26, 1919. Serial No. 299,832.

To all whom it may concern:

Be it known that I, ARTHUR F. CASE, a citizen of the United States, residing at Cleveland, in the county of Cuyahoga and 5 State of Ohio, have invented a certain new and useful Improvement in a Fueling Barge, of which the following is a full, clear, and exact description.

The present invention relates to a fueling 10 barge for fueling steamships. The principal object of the invention is to provide an efficient boat fueling machine or apparatus which has the advantage of considerable storage capacity, which is adaptable for 15 feeding fuel into hatches which are on the top of the boat, or for side hatch fueling, and which raises the coal or fuel only to a height necessary to feed into the proper hatch without requiring that it be elevated 20 to a considerable height above the hatch as is necessary with the so-called gravity systems.

Further the invention aims to provide a fueling barge carrying means by which the 25 barge itself may be loaded with fuel, as by a revolving derrick carrying a grab bucket, and also means by which the fuel is discharged from the barge into a steamboat through the medium of a conveyor on a lat- 30 erally extending boom to which coal is delivered, and which is capable of being moved up and down a tower, and may be tilted about its inner end or swung horizontally so that the material may be discharged at 35 just the right height, and at the proper hatch without elevating the fuel any higher than necessary, the whole being so constructed that though it operates very effectively in fueling a boat irrespective of the 40 height of the hatch openings or their distribution along the length of the boat, but nevertheless when the barge is being conveyed from point to point, the movable parts utilized in loading and unloading the barge 45 can be lowered so as to avoid excess of superstructure which might produce instability.

The above and other objects are attained by my invention which may be here briefly summarized as consisting in certain novel 50 details of construction and combinations and arrangements of parts which will be described in the specification and set forth in the appended claims.

In the accompanying sheets of drawings, 55 Fig. 1 is a side view of a fueling barge con-

structed and equipped in accordance with my invention; Fig. 2 is a top plan view of the same; Fig. 3 is a transverse sectional view; Fig. 4 is a similar sectional view but showing in side elevation the superstructure including the hoppers utilized in loading the barge, and the tower up and down which the unit including the delivery boom is adapted to be moved; Fig. 5 is a fragmentary transverse sectional view on an enlarged scale, showing particularly the conveyors utilized in fueling two sets of storage hoppers and in delivering the fuel therefrom; Fig. 6 is a fragmentary elevation showing particularly the fuel elevator and part of the apparatus for feeding the fuel thereto, as well as the unit which is moved up and down the tower including the boom which delivers the fuel laterally into the boat hatches, the tower itself being omitted for the sake of clearness; Fig. 6^a is a view showing the extreme top of the tower and the sheaves or sprockets mounted at this point; Fig. 7 is a sectional view substantially along the line 7—7 of Fig. 6; Fig. 8 is a sectional view substantially along the line 8—8 of Fig. 6; Fig. 9 is a sectional view substantially along the line 9—9 of Fig. 6; and Fig. 10 is a transverse sectional view through the boom.

By way of preliminary explanation it might be mentioned that my improved fueling barge has a series of storage hoppers preferably arranged in sets or groups to which fuel is adapted to be delivered in fueling the barge by any suitable conveying mechanism which is preferably supported at one end of the barge, and in this case consists of a revolving derrick carrying a hoisting and conveying bucket which delivers the fuel into suitable hoppers so arranged that the fuel may be carried from these hoppers to the storage hoppers. For the purpose of filling and also emptying the storage hoppers, as when a boat is being fueled, a series of conveyors are utilized, each serving one set of the storage hoppers, and arranged to travel in a closed circuit over the storage hoppers in connection with which suitable gates or doors are employed for the admission of fuel therein, then downwardly and along beneath the storage hoppers which have suitable chutes or delivery orifices arranged so that the fuel may be discharged from the bottoms of the hoppers.

onto the lower traveling flights of these conveyors. The lower sections of these conveyors which receive and deliver the fuel from the bottoms of the storage hoppers, 5 carry the fuel toward the transverse center line of the barge and discharge the fuel onto transverse conveyors which in turn deliver the fuel to an elevator boot.

From this boot the fuel is conveyed by the 10 elevator composed of chains and elevating buckets which travel up the tower positioned at or adjacent the center of the barge, this elevator passing around a tripper and discharging into a hopper which delivers 15 the fuel onto a conveyor carried by a delivery boom which delivers the fuel into the boat hatches, this tripper and the boom as well as other parts associated therewith forming a unit which can be raised and lowered 20 along the tower in accordance with the required delivery height of the fuel. Additionally the unit has provision for turning the boom and for swinging it about a transverse axis near its inner end, so that its delivery 25 end may be raised and lowered without elevating or lowering the unit as a whole.

The above general or preliminary explanation will make clear the following detailed explanation of the construction and 30 operation.

The barge 10 in this instance contains four sets or groups of storage hoppers arranged substantially in the four quarters of 35 the boat and designated respectively 11^a, 11^b, 11^c and 11^d, there being in this case four hoppers in each set. The two groups 11^a and 11^d and the two groups 11^b and 11^c are 40 respectively arranged on opposite sides of the longitudinal center line of the barge, and the two groups 11^a and 11^b are arranged on one side of a transverse plane through the barge near the center, and the two groups 11^c and 11^d are on the opposite side 45 of the same.

To charge or fill these hoppers the barge is provided at one end with a revolving derrick 12, of customary design, construction and operation, mounted so that it may be 50 swung laterally, and raised and lowered about its inner or lower end. The derrick carries a hoisting and conveying bucket 13, which may be of the clam-shell type, and which will have such capacity that a fairly 55 large quantity of fuel can be delivered to the barge at one trip of the bucket. It will be understood that with this hoisting and conveying apparatus including the derrick and bucket, fuel may be loaded onto the 60 barge from any suitable source of supply which may be on a pier alongside of which the barge may be tied or anchored, or which may be on another barge alongside the fueling barge. As a matter of fact, fuel may be 65 loaded into the fueling barge at the same

time that it is being delivered therefrom to fuel a boat, or it may be delivered into the barge while the fueling apparatus is idle.

The bucket 13 delivers the fuel into two hoppers 14, 14, located near the center of the barge on opposite sides of the longitudinal center line of the barge. From these hoppers 14, 14, the fuel is delivered by delivery spouts 15, to four conveyors 16, two extending 70 forwardly in parallel lines or planes, 75 and delivering fuel to two sets of storage hoppers 11^a and 11^b, and two extending rearwardly in parallel lines or planes, and delivering fuel to the sets of storage hoppers 11^c and 11^d. Each of these conveyors 80 includes two endless chains connected together with scraper plates or blades 16^a (see Fig. 5) and extending horizontally over one set of hoppers this section of the conveyor traveling from the center toward 85 the end of the barge. Then the conveyor travels vertically downward to nearly the bottom of the barge, then horizontally inward toward the center, and up to the upper level. These conveyors each pass about suitably positioned pairs of sprockets 16^b, and they are preferably driven by four separate motors 16^c located adjacent the outer ends of the conveyors and each suitably geared to one pair of sprockets. 90

The upper sections of the conveyors scrape the fuel along horizontal troughs 17, see particularly Fig. 5, which are on top of the storage hoppers, and the fuel may pass from these troughs as it is moved along the 100 same through doors or gates 18 which are provided in the bottom of each trough, one over each hopper. These gates or doors may be of any suitable form, and operated in any desired manner, but in this instance they are of the sliding type, being adapted to be moved in and out by horizontal lateral arms 19 having racks, each engaged by a pinion 20 on the lower end of a vertical shaft 21 on top of which is a hand-wheel 22. 110 These hand-wheels are on opposite sides of walks 23, which extend forwardly and rearwardly lengthwise of the boat, one between the hoppers 11^a and 11^b, and the other between the hoppers 11^c and 11^d. This is clearly indicated in Fig. 5. With this construction, any of the hoppers can be filled by opening the gates and the supply of fuel thereto may be terminated by closing the gates. 115

These same conveyors are employed in removing the fuel from the storage hoppers when it is desired to fuel a boat, and to that end the lower horizontal traveling sections of the conveyors travel along lower 125 troughs 24, which are beneath the delivery chutes 25 at the lower ends of the hoppers. The plates or blades 16^a of the conveyors 16 scrape the fuel along these troughs inwardly toward the center of the barge where the 130

troughs extend upwardly as shown at 24^a in Fig. 6, and at their inner ends these troughs have delivery pans or aprons 25^a, (see Figs. 5 and 6) which deliver the 5 fuel onto two inclined cross conveyors 26 shown in Fig. 5, which may be motor driven through gearing indicated at 26^a, each conveyor 26 comprising chains with scraper blades 26^a (see Figs. 5 and 6), and operating 10 in inclined troughs 27 the chains passing about sprockets 26^b shown in Figs. 5 and 6. That is to say, the fuel is delivered from the sets of storage hoppers 11^a and 11^d into the trough of one cross-conveyor, and the 15 fuel from the other two sets of storage hoppers 11^b and 11^c is delivered into the trough of the other cross-conveyor.

The inner ends of these conveyor troughs discharge the fuel near the center of the 20 barge into an elevator boot 28 (Figs. 1, 5, and 6), and from this boot the fuel is carried upwardly by an elevator composed of chains 29 having a series of elevating buckets 30, the fuel being elevated in a vertical tower 25 31 which stands up from near the center of the barge. This tower is shown only conventionally inasmuch as it may be formed of structural material in any suitable manner, it being important only that it effectively 30 support the delivery apparatus which is movable up and down the tower and which delivers the fuel into the hatches.

The chains 29 of the elevator pass around lower sprockets 32, suitably mounted in the 35 boot 28, and around similar sprockets 33 mounted at the top of the tower.

Between the upper and lower sprockets the elevator chains pass around a tripper which causes the material to be discharged from 40 the buckets, this tripper forming a part of the apparatus including the delivery boom and constituting the unit movable up and down the tower, if being understood that the height to which the fuel is elevated by this 45 elevator may be varied by raising and lowering the vertically movable unit. The tripper includes sprockets 34 and 35, over which the elevator chains carrying the loaded buckets travel (see Fig. 6), the chains making a 50 loop around the sprockets 34 and 35 so as to tip the buckets and cause the fuel to be discharged therefrom in a well known manner. From the sprockets 35 the chains of the elevator pass around additional tripper 55 sprockets 36 which are directly above the before mentioned sprockets 34, and from these sprockets the chains pass upwardly around the before mentioned sprockets 33 at the top of the tower. It might be mentioned 60 at this point that the elevator is preferably driven by a motor 37 (see particularly Fig. 7), supported on a platform 38, forming a part of the unit which moves up and down the tower. The motor drives the elevator 65 through the medium of a pinion 39 which

meshes with a gear 40 on a shaft 41, having a pinion 42 which drives a gear 43 on a shaft 44 to which the sprockets 35 are attached.

The unit which moves up and down the 70 tower is shown separate from the tower in Fig. 6, all the apparatus shown by full lines except that at the bottom of Fig. 6, and which serves to deliver the fuel to the elevator boot, forming the unit which moves 75 along the tower.

By reference to Figs. 7, 8, and 9, it will be observed that the unit is provided with suitably flanged wheels 45, which engage vertical guiding and supporting rails 46 80 secured to opposite sides of vertical channels 47. The unit can be raised and lowered by a suitable hoisting and lowering apparatus including a motor driven drum (not shown) which will be mounted on the barge 85 near the base of the tower, and which receives a hoisting and lowering cable which I have indicated at 48 in Fig. 6. This cable 48 is preferably dead-ended at the top of the tower, as shown at 49 in Fig. 6, and then 90 passes downwardly around a sheave 50 (Fig. 6) carried by the vertically movable unit, then upwardly around a sheave 51 (Figs. 1 and 6^a) supported at the top of the tower, and then down to the hoisting and lowering 95 drum.

When the elevator chains and buckets pass around the tripper, the fuel is delivered 100 into a chute 52 which extends downwardly beneath the platform 38 near the top of the unit as before explained. This chute 52 delivers the fuel into a hopper 53 mounted on the inner end of a delivery boom 54, which is mounted so that it may be swung about a transverse axis to raise or lower its outer end, and may be swung about a vertical axis to deliver the fuel at any angle within substantially a half circle with reference to the longitudinal axis of the barge. The hopper 53 discharges the fuel onto a belt conveyor 55, which carries the fuel out to the outer end of the boom, and which travels around main sheaves or drums 56 and 57 at the inner and outer ends of the boom, and around other suitable supporting rollers or sheaves 54^a, the top leg or section of the conveyor belt being dished, with its edges higher than the center so as to prevent spillage of fuel in a well known manner (see Fig. 10). The mechanism for driving 110 the delivery belt 55 as well as for turning the boom and tilting the same is all carried by the movable unit, as will be explained shortly.

The boom is pivotally mounted (by means 125 to be hereinafter described) at the top of a vertical supporting arm 59, (see Fig. 6) which at its lower end is rotatably supported through the medium of a ball and socket step bearing 60, the socket part of the bear- 130

ing being carried by a support 61 at the bottom of the vertically movable unit. The arm 59 passes through and is adapted to turn with a platform or turntable 62, on the lower side of which are rotatably supported a series of guide rollers 63 (see Figs. 6 and 9), which rollers engage the inner periphery of a circular guide track 64, on the outer periphery of which is a rack segment 65. This rack segment is engaged by a pinion 66 (see Fig. 6), mounted on a short vertical shaft 67, carried by the platform 62, and provided at its upper end with a bevel gear 68 (see Figs. 6 and 9), designed to be rotated by a bevel gear 69 on the short horizontal shaft 70 having a gear 71 engaged by a pinion 72 on a shaft 73, provided with a sprocket 74, these driving gears, shafts and the like being all carried by the platform 62, as will be apparent from Figs. 6 and 9. It will be understood that when the sprocket 74 is turned, the boom 54, supporting arm 59, and platform 62 will be turned about the axis of the circular trackway 64. The sprocket 74 is driven by a chain 100, hereinafter described.

To tilt the boom about its pivotal axis, the following mechanism is shown, particularly in Figs. 6 and 9. The inner end of the boom which projects a short distance rearwardly of the pivotal axis is connected by a pair of straps 75 to a nut 76 adapted to travel up and down a threaded vertical shaft 77. To turn this shaft in either direction there is provided on the lower part of the shaft a bevel gear 78 which is engaged by a bevel gear 79 (see Fig. 9), secured to a short horizontal shaft 80, provided with a gear 81 which is driven by a pinion 82 on a horizontal shaft 83, provided with a sprocket 84. It will be seen that when the sprocket 84 is turned in one direction, the nut 76 will be moved either up or down the threaded shaft 77 so as to raise or lower the outer end of the boom, as the case may be, and when the sprocket 84 is rotated in the opposite direction, the outer end of the boom will be moved in the opposite direction to that in which it was moved when the sprocket was rotated in the direction first referred to. The parts designated by the reference characters 77 to 84 inclusive, are mounted directly or indirectly on the rotary platform 62. As will be explained subsequently, the sprocket 84 is rotated by the chain 101.

For the purpose of driving the delivery belt 55 extending along the boom, and for rotating the sprockets 74 and 84 which respectively turn and tilt the boom, I mount on a platform 85, (see Fig. 8) carried by one side of the boom supporting arm 59, a motor 86, which through reduction gears, one of which is shown at 87 in Fig. 8, drives a horizontal shaft 88 which extends through

the upper ends of the boom supporting arm 59 and directly through the boom, the latter being provided with a sleeve 88^a fixed in the sides of the boom, and turning on the shaft 88. The center of this shaft constitutes the axis about which the boom is adapted to be tilted as before stated. This shaft 88 through the medium of a clutch 89, is adapted to rotate a sprocket 90, which through a chain, indicated at 91 in Fig. 8, rotates a sprocket 92 on a shaft 93, which extends through the boom, and on its end opposite to that having the sprocket, is a pinion 94 which drives a gear 95 fixed to the shaft 96 to which is secured the rear drum 56 about which the delivery belt 55 of the boom passes. It will be seen that when the clutch member 89 is shifted so as to clutch the sprocket 90 to the shaft 88, the shaft 96 and drum 56 are rotated, and this in turn drives the delivery belt 55.

It is through this same shaft 88 which drives the delivery belt 55, that the two sprockets 74 and 84 already referred to, are rotated to swing the boom and to tilt it. For that purpose, the end of the shaft 88 which projects through and beyond the boom is provided with a pair of sprockets 97 and 98 (see Fig. 8), either of which is adapted to be clutched to the shaft 88 by a clutch member 99. When the sprocket 97 is clutched to the shaft it drives the boom rotating sprocket 74 through the medium of a chain 100, shown in Fig. 6. When the sprocket 98 is clutched to the shaft 100 it rotates the boom tilting sprocket 84 through the medium of a chain 101, likewise shown in Fig. 6.

The operation of the machine will be apparent from the above description considered in connection with the drawings, and by way of recapitulation it might be stated that the storage hoppers are loaded through the swinging derrick and bucket which deliver the fuel into the hoppers 14 from which the fuel is taken by the four conveyors 16 and moved along the troughs 17 and delivered into the tops of the storage hoppers when the gates 18 are open. By selectively opening and closing these gates it is apparent that the hoppers can be filled as desired. It was already stated that the filling of the hoppers can take place while the delivery apparatus is idle, or at the same time that the boat is being fueled. In any event, the same conveyors 16 which deliver the fuel to the storage hoppers convey the fuel from the lower ends or bottoms of the hoppers to the cross conveyors 26 which discharge the fuel into the elevator boot 28. From this the fuel is carried up to the tower by the buckets 30 on the elevator chains 29, and as the elevator passes around the tripper, fuel is delivered into the chute 52, then into the hopper 53 which is directly above the belt 130

55 of the boom, and by the latter is carried to and delivered into the boat hatches.

- The boom can be raised and lowered to deliver the fuel at the right height by raising or lowering by means of the rope or cable 48 the unit which moves up and down the tower, or if desired, or found feasible, the height of delivery can be varied by simply tilting the boom. At any rate, with the 10 mechanism which I have provided, it is not necessary to elevate the fuel much if any higher than the hatch openings of the boat being fueled. This is a big advantage over so-called gravity systems which require that 15 the fuel pass by gravity from some elevated point into the boat hatches. Obviously with my fueling apparatus, power is saved by delivering the fuel no higher than necessary, and there is a minimum of breakage.
- 20 The boom can be raised and lowered readily, and it can be easily tilted or swung horizontally by the mechanism which I have provided, it being understood that the boom is tilted by operating the sprocket chain 101, and is swung laterally by operating the sprocket chain 100.

The barge can be conveyed from point to point either by means of a tug, or if desired, propelling mechanism may be installed directly on the barge. When the barge is being conveyed or propelled from one point to the other, the derrick of the 30 hopper loading apparatus and the unit which moves up and down the tower, including the boom will be lowered as close as possible to the top of the storage hoppers so that the center of gravity will not be high which makes for stability in transit.

To furnish current to energize the several 40 driving motors which operate the different conveyors, which raise and lower the vertically movable unit along the tower, and which turn and tilt the boom, an engine generator set is preferably provided on the barge.

While I have shown only one form of my invention it will be obvious that many changes may be made in details of construction and arrangement, and I therefore do 50 not desire to be confined to the construction shown, but aim in my claims to cover all modifications which do not involve a departure from the spirit and scope of my invention in its broadest aspects.

55 Having described my invention, I claim:

1. A fueling barge having a series of storage hoppers, a conveyor having a portion extending over the hoppers so that it may deliver fuel thereto, and having a portion extending beneath the hoppers so that it may carry fuel therefrom, means for supplying the fuel to the upper part of said conveyor so that it may be delivered to 60 the hoppers, and means for receiving the

fuel from the lower part of said conveyor and delivering the same to a boat to be fueled comprising a cross conveyor to which the fuel is delivered by the first-named conveyor, and an elevator for receiving the 70 fuel from the cross conveyor.

2. A fueling barge having a series of storage hoppers with openings at the top adapted to receive fuel, and discharge openings at the bottom, a conveyor having a section extending over the hoppers so that it may supply fuel thereto, and a section extending beneath the hoppers and adapted to convey the fuel therefrom, means for feeding fuel to the upper section of the conveyor and means for delivering fuel from the lower section of the conveyor comprising a cross conveyor adapted to receive fuel from said conveyor, a substantially vertical elevator for receiving fuel from the cross 80 conveyor, and a lateral delivery member for receiving fuel from the elevator.

3. A fueling barge having a plurality of sets of hoppers located part on one side and part on the other side of the longitudinal axis of the barge, and having an apparatus for delivering fuel therefrom into a boat to be fueled, said apparatus comprising a vertical elevator located centrally with respect to the sets of hoppers and a plurality of conveyors for conveying fuel from the different sets of hoppers to the elevator.

4. A fueling barge having a plurality of hoppers arranged in longitudinally extending rows both fore and aft of the center of the barge, and on opposite sides of the longitudinal center line of the barge, means for delivering fuel from said hoppers comprising a plurality of longitudinally extending conveyors extending beneath the same, cross 100 conveyors at substantially right angles to the first named conveyors and receiving fuel therefrom, and an elevator to which said last mentioned conveyor delivers the fuel said elevator being located near the center 105 of the barge.

5. A fueling barge having a plurality of sets of hoppers arranged on both sides of the longitudinal and transverse center lines of the barge, means for delivering fuel from 115 said hoppers comprising a plurality of conveyors extending beneath the same lengthwise of the barge, a plurality of cross conveyors at substantially right angles to the first named conveyors and receiving fuel therefrom, and an elevator to which said last mentioned conveyors deliver the fuel said elevator being arranged substantially 120 centrally with respect to the said sets of hoppers.

6. A fueling barge having fuel storage means, a vertical tower, an endless elevator for elevating the fuel in the tower, means for delivering fuel from the storage means to the elevator, and a delivery boom project- 125 130

ing laterally from the tower, said boom being mounted for movement up and down the tower and for lateral swinging movement, said elevator having a point of dis-

5 charge adjustable vertically with the up and down movements of the boom with respect to the tower.

7. A fueling barge having fuel storage means, a vertical tower, an endless elevator 10 for elevating the fuel in the tower, means for delivering fuel from the storage means to the elevator, and a boom projecting laterally from the tower and having a conveyor for delivering fuel to a boat to be fueled, 15 said boom being mounted for movement up and down the tower and for tilting movement about its inner end, and means by which the delivery point of the conveyor moves up and down with the up and down 20 movements of the boom with respect to the tower.

8. A fueling barge having fuel storage means, a vertical tower, an endless elevator for elevating the fuel in the tower, means 25 for delivering fuel from the storage means to the elevator, and a delivery boom projecting laterally from the tower, said boom being mounted for movement up and down the tower, for lateral swinging movement 30 and for vertical swinging movement with reference to the tower and means movable vertically with respect to the tower when the boom is moved up and down the same for varying the point of discharge of the 35 elevator so that the fuel will be received on the boom regardless of the position to which it is adjusted up or down with respect to the tower.

9. A fueling barge having storage means 40 for fuel, a tower projecting upwardly from the barge, an endless elevator for conveying fuel up the tower, means for delivering fuel from the storage means to the elevator, and a unit movable up and down the tower and 45 comprising a tripper by which the fuel is caused to be discharged from the elevator and a laterally projecting boom with a con-

veyor extending along the same and adapted to receive the fuel when discharged from the elevator the boom conveyor being separate 50 from the elevating means.

10. A fueling barge having storage means for fuel, a tower projecting upwardly from the barge, an endless elevator for conveying fuel up the tower, means for delivering fuel 55 from the storage means to the elevator, and a unit movable up and down the tower and comprising a tripper by which the fuel is caused to be discharged from the elevator and a laterally projecting boom adapted to 60 receive the fuel when discharged from the elevator, the boom being mounted for swinging movement with reference to the tower and tripper.

11. A fueling barge having storage means 65 for fuel, a tower projecting upwardly from the barge, an endless elevator for conveying fuel up the tower, means for delivering fuel from the storage means to the elevator, and a unit movable up and down the tower and 70 comprising a tripper by which the fuel is caused to be discharged from the elevator and a laterally projecting boom adapted to receive the fuel when discharged from the 75 elevator, the boom being mounted for tilting movement with reference to the tower and tripper.

12. A fueling barge having storage means for fuel, a tower projecting upwardly from the barge, an endless elevator for conveying 80 fuel up the tower, means for delivering fuel from the storage means to the elevator, and a unit movable up and down the tower and comprising a tripper by which the fuel is caused to be discharged from the elevator 85 and a laterally projecting boom adapted to receive the fuel when discharged from the elevator, the boom being mounted for lateral swinging movement and for vertical tilting 90 movement with reference to the tripper and tower.

In testimony whereof, I hereunto affix my signature.

ARTHUR F. CASE.
